DRAPEY MOUNTING

Goldie Rosenberg, Brooklyn, N. Y.

Application July 16, 1935, Serial No. 31,571

8 Claims. (Cl. 156—10)

This invention relates to means for, and the method of, mounting drapery and decorative fabrics, generally.

The principal object of this invention is to provide means of support on a drapery, which may replace the ordinarily used supporting means, e. g., rods, cornices, etc., and which fixedly determine the disposition of the drapery as a whole or in part.

More particularly my invention provides for a filler for folds or pleats of a drapery, said folds or pleats being stuffed or filled with such filler or being extended or stretched thereover.

According to the nature or permanency of the arrangement of a drapery, various materials may be used for the fillers. A padding, hose or a coiled spring offer flexibility and yieldability for the purpose of an inexpensive, curved arrangement. Structural members such as solid or assembled lumber or profiles of metal or plastics come into question for more permanent installations. A very convenient structural member is tubing of transparent material, compositions or metals, or for instance sheet material which is extended spirally or along central seams.

This invention is readily adaptable to styles or periods. As a matter of fact it offers a more flexible and independent means to the ingenious interior decorator, since he may readily depart from the conventional supporting means of the prior art.

Modern illuminative devices may be incorporated in the mountings of my invention, and from an aesthetic, as well as a practical, point of view, a great number of other objects may be attained, which are more readily understood from the following description. The said description has reference to the exemplary showings of the drawing, in which

Fig. 1 shows the elevation of a drapery disposed as a Roman arch, the lower, freely falling ends of the drapery being sectioned away.

Fig. 2 shows a cross-section of the drapery taken along a line pointed out in Fig. 1 by arrows and the numerals 2.

Fig. 3 shows the symmetrical half of the elevation of another drapery arranged in a more bold modern style.

Fig. 4 shows a corresponding top view.

Fig. 5 shows in a plan view a spread to which my improvements have been applied.

Figs. 6, 7 and 8 show various modifications of my invention in end views.

Fig. 9 shows a detail view of a developed sec-

tion of the drapery used in the modification of Fig. 1.

Similar numerals refer to similar parts throughout the various views.

In the arrangements of Figs. 1 and 2, wooden fillers are exemplarily used. The wooden fillers 11, 12, 13 and 14 are arranged in parellism and in concentricity at their straight and curved portions, respectively. The drapery 15 encircles each one of these lumber rods, the pleats of the drapery filled by the rods being exemplarily disposed in abutment.

One end 16 of the drapery 15 freely depends from one end of the rods; whereas the other end 17 of the drapery, to the left, is gathered in by a tie-back 18. Supplementary decorative means such as trimmings in the form of cord 19 or ruffle 20, may be applied according to the fancy of the decorator.

It will be understood that a crowding of the drapery will occur on the innermost rod 14, as compared for instance with the outermost rod 11, unless different lengths of strips of drapery are provided for in the instance of each stuffed pleat or roll. Under such circumstances I may cut the drapery into strips as a whole or in part. Thus I may resort to the following arrangement in the particular instance of the modification of Fig. 1. The end 16 of the drapery 15 is a solid piece. But extensions 21 thereof, which are wrapped and sewed individually around the rods 11, 12, 13 and 14, are separated from each other, beginning at 22, by slits 22. Where the slit-apart strips or extensions 21 extend from the left ends of rods 11, 12, 13 and 14, they may be sewed together at their slit edges; and at a convenient point, for instance underneath the tie-back 18 a solid section 23 of drapery material, of the width of the reassembled strips 21 or the other end 16 of the drapery, may be pieced to the ends of said strips 21 at a convenient point, for instance underneath the tieback 18; the rods 11, 12, 13 and 14 may be suitably mounted either upon a window sash or upon a wall or upon a suitable backing 24.

In the arrangement of Figs. 3 and 4, the drapery is applied, for economic reasons or for the purpose of variegation, in separate sections 25 and 26, for the valance and the sides, respectively. As fillers I show round tubing 27, in this instance, and it fills the pleats, e. g., 28, which are formed by seams 29 running down along the whole length of the material of the drapery in the back thereof.

The lower ends of the fillers 27 may be attenu-

ated, tapered or contracted, so that the lower ends 29 of the drapery close thereover in an orderly fashion at the ends of the fillers. Fig. 5 shows the principle of my invention applied to a spread. The covering material of the spread exemplarily comprises, in the showing of Fig. 5, three sections; section 31 is sewed onto section 32 along a seam 33. In section 32 are formed the pleats 34, which are partly stuffed, at their upper 10 (lower in the drawing) ends by fillers 39. The fillers in this instance would of course be made of a soft material like cord or cotton padding. The upper ends 35 of the said stuffed pleats are superimposed and sewed onto piece 31 of the 15 fabric of the spread, and the lower ends 36 of the pleats depend loosely, gravitationally from the stuffed upper part thereof. A third piece of material 37 used in making the spread of Fig. 5, consists of stuffed pleats only, said pleats being independent of each other, if they correspond to the 20 arrangement of Fig. 2, or being interconnected if they are arranged in accordance with Fig. 4. This pleated piece 37 with its stuffed pleats may be sewed at its upper (left on the drawing) end 25 onto the right end 38 of piece 31.

Where a drapery is loose in the manner of a spread, the stuffed pleats may be sewed or tacked on as the occasion may seem fit. When the filler is made of wood, in the manner of Fig. 2, it may 30 readily be nailed onto a backing. The fillers may be suspended in the pleats and the pleated stuffed material may be mounted on a backing, as it suggests itself with the drapery arranged in the manner of claims 3 and 4.

35 Cementing might be used, as I had it in mind for the purpose of mounting the triangular tubular fillers 41, by way of the folded back strips of drapery 42, onto the backing 43. In Figs. 7 and 8 I indicate bolts and nuts 44 or screws 45 for the same purpose.

40 Tubular fillers may of course assume any preferred cross-section and may be extended straight or in waves, e. g., entwined. Should the effect of hexagon fillers be desired, the hexagon effect from the front may also be attained by using 45 semi-hexagonal tubing 46; and in Fig. 7, the drapery material 47 is clamped by means of bolts 44 onto a backing 48, the head of the bolt being accommodated upon the inside of the semi-hexagonal tube.

50 Other polygonal or oblong cross-sections may be resorted to; the filled pleats may also be predeterminedly spaced apart as indicated in Fig. 8. Of course the cross-sections of the filler may be 55 assembled.

Thus Fig. 8 shows flat metal strips 51 to be

spaced apart by lugs 52 soldered therebetween. The material 54 of the drapery is retained in a position in which it is stretched over the gap 53 between the flats 51 by being clamped at the fold of the pleats between the back of the assembled 5 filler, (the flats 51), and the backing 55.

When the structural members or tubes of the fillers are transparent or translucent, or are constructed in an open fashion like that of Fig. 8, illuminating means, e. g., lamps 56 may depend 10 into the fillers, or be mounted therein, and will shine through the drapery enveloping the filler.

In addition to the above outlines of the various constructions and the operation of the device, a large number of other modifications of its construction and operation suggest themselves to those skilled in the art, and may be applied under proper conditions. They fall within the general scope of this invention, as outlined in the following claims.

20 What I claim is:—

1. In combination, a drapery formed into a series of pleats, a filler located in each pleat to support the same against collapse, and means for hanging the drapery.

25 2. In combination, a drapery formed into a series of tubular pleats, and a stiffening rod disposed in each tubular pleat to support the same against collapse.

3. In combination, a drapery formed into a 30 series of closed tubular pleats, and a stiffening filler inserted in each tubular pleat and having a form corresponding to that of the drapery.

4. In combination, a drapery formed into a 35 series of tubular pleats having their sides connected to each other, and a stiffening filler inserted in each tubular pleat.

5. In combination, a drapery having a series 40 of decorative pleats and a filler inserted in each pleat to support the same against collapse.

6. In combination, a drapery constructed of 45 fabric material and formed with a series of decorative pleats disposed in an arc, and a stiffening filler inserted in each pleat.

7. A drape of the class described, comprising 50 a body portion, said body portion provided with a series of pleats, the contacting edges of said pleats being secured together to provide pockets, and means in said pockets to give a fixed design to said drapes.

8. In combination a drapery having a series of 55 concentric pleats each formed of an independent strip of fabric and having a filling material therein and said pleats being attached together along their meeting edges.
